INTERNAL-COMBUSTION ENGINE

Charles N. Aronson, Niagara Falls, N. Y.

Application September 1, 1944, Serial No. 552,349

2 Claims. (Cl. 123—73)

This invention relates to new and useful improvements in internal combustion engines of the two-cycle type wherein a rotary valve is generally employed to introduce the combustible charge into the crankcase on the up-stroke of the piston and where the charge is subsequently compressed on the down-stroke. In the conventional engine of this type, it has been customary to cut slots in the regular size main bearing journals and due to the small normal size of these journals, the slots had to be quite small.

It is the principal object of the present invention to provide an engine of the two-cycle type wherein the fuel charge is compressed within the crankcase with enlarged bearing journals formed with fuel admission slots and wherein the large journals are formed to a running bearing fit in the crankcase itself.

Another important object of the invention is to provide journals of the character stated which because of their size have a flywheel effect, thus eliminating the need for a flywheel and because of the presence of these large journals between the cylinders with their flywheel effect, the engine has a tendency to run much smoother than otherwise.

Still another important object of the invention is to provide journals of the character stated especially for two-cycle engines which because of their size will be far easier to grind than those present in most conventional types of engine.

Still a further object of the invention is to construct a motor with journals of the character stated which will have an overall simplicity which will permit its manufacture at a much lower cost than engines of this type.

Various other important objects and advantages of the invention shall become apparent to the reader of the following description.

In the drawing—

Figure 1 represents a fragmentary vertical sectional view through a two-cycle engine showing the journals as improved.

Figure 2 is a vertical sectional view (fragmentary) taken on the line 2—2 of Figure 1.

Figure 3 is a top plan view of the improved crankshaft.

Referring to the drawing wherein like numerals designate like parts, it can be seen in Figure 1 that numeral 5 denotes a crankcase from which rise cylinders 6.

The crankcase is formed to directly contact the journals of the improved crankshaft generally referred to by numeral 7.

As shown in Figure 3, the shaft 7 includes end

journals 8, 9 which are not slotted for the admission of fuel. Spaced between the journals 8, 9 are three large journals 10, 11 and 12. Assuming that this crankshaft is to take care of a four-cylinder engine, it can be seen that the journal 10 is slotted at 13 to open through one side thereof to accommodate one end cylinder. This same journal 10 is slotted as at 14 to open at its opposite side to take care of a cylinder next to said end cylinder.

The journal 11 is unslotted, but the journal 12 is slotted in the same manner as the journal 10, the same having a slot 15 opening through one side to accommodate the other end cylinder and a slot 16 opening through the opposite side of the same to accommodate the cylinder next to the last-mentioned end cylinder.

Thus it can be seen, that at each side of the slotted journals 10, 12, there is an unslotted journal, these unslotted journals being denoted by numerals 8, 11 and 9.

As can be seen in Figure 2, the side of the crankcase 5 has a manifold 17 communicating with channels 18 opposed to the journals 12 and 10. Thus it can be seen, that for the period of the up-stroke of a piston, fuel is being taken in to the crankcase, below its piston by way of the manifold 17, channel 18 and slot in the journal. Of course, on the down-stroke this charge is compressed.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

1. In an engine of the character stated comprising a crankcase, a plurality of cylinders, a crankshaft, said crankshaft being provided with alternately slotted and unslotted enlarged journals, the ends of the crankshaft being provided with unslotted journals, each slotted journal being formed with two slots opening through opposite sides of the journal, and means for supplying fuel to the crankcase compartments defined by the journals by way of said slots for compression by pistons in the cylinders.

2. In a two-cycle engine, a crankcase, a crankshaft, said crankshaft being provided with an enlarged cylindrical journal fitted rotatably but tight in a circular opening in a part of the crankcase constituting a wall of a fuel supply compartment for a working cylinder of the engine,

said crank case having a fuel charge admission channel the open side of which is communicable throughout a substantial distance annularly of the crank shaft journal, said fuel charge admission channel being generally covered in closing relation by said crank shaft journal, said crank shaft journal being formed with a transverse

5 peripheral fuel conducting slot which is closed at one end and open at its other end at one side of the journal and communicable with the adjacent fuel supply compartment during a part of the rotation of said journal.

CHARLES N. ARONSON.
